UNITED STATES PATENT OFFICE.

JOHN O'BRIEN, OF NEW YORK, N. Y., ASSIGNOR TO WILLIAM BROOKFIELD,
OF SAME PLACE.

TELEGRAPH-INSULATOR.

SPECIFICATION forming part of Letters Patent No. 316,812, dated April 28, 1885.

Application filed December 18, 1884. (No model.)

To all whom it may concern:

Be it known that I, JOHN O'BRIEN, a citizen of the United States, residing at New York, in the county and State of New York, have invented new and useful Improvements 5 in Telegraph-Insulators, of which the following is a specification.

This invention consists in a telegraph-insulator having within its body a transverse hole 10 extending in a straight line from side to side thereof, and provided with a rectilinear side entrance approximately the length of the transverse hole, and having its lower edge extended laterally in an outward direction beyond the 15 upper edge and terminating below the latter to leave the rectilinear side entrance unobstructed for the lateral insertion of the line-wire.

The invention also consists in other features, which will be hereinafter described and claimed.

In the accompanying drawings, Figure 1 represents a vertical central section in the plane x x , Fig. 2. Fig. 2 is a face view. Fig. 25 3 is a face view of two insulators secured on telegraph-poles with the wire extending through the insulators, on a smaller scale than the previous figures.

Similar letters indicate corresponding parts. 30 In the drawings, the letter A designates a telegraph-insulator, which is, by preference, made of glass, but which may be made of any other material suitable for the purpose.

The insulator shown in the drawings is provided with an internal screw-thread for the purpose of securing the same in position on a telegraph-pole; but my invention is not restricted to screw-insulators, since it can be applied to insulators provided with other suitable means for securing the same in position 40 on a telegraph-pole.

In my insulator is formed a transverse hole, a , which forms a passage for the wire, and which extends in the line of the wire, and the 45 wire is introduced into this hole through a side entrance, b , which is just wide enough to admit the wire. The sides of this side entrance are rectilinear and not winding or spiral, so that the wire can be readily passed through 50 into the hole a . It will be seen from this de-

scription that the wire, when once introduced into the hole a , will be supported in an upward as well as in a downward direction, and at the same time no tie-wire is required, and the line-wire can be drawn tight during the operation 55 of putting it up with the greatest ease by a man standing on the ground, and it can also be readily tightened up if ever it should be desirable. The lower edge or lip, c , of the side entrance, b , projects laterally in an outward direction beyond the upper lip, c' , and terminates below the latter, so that it forms a guide to conduct the wire into the hole a .

In order to guard against the danger that the wire may be accidentally forced out of the 65 hole a through the side entrance, b , by gusts of wind or other causes, the side entrance is made oblique in regard to the axis of the hole, or to the direction in which the line-wire runs; and by referring to Fig. 3 it will be readily seen 70 that with an oblique side entrance the wire is not liable to be thrown out of the hole a by the strongest wind or otherwise. At the same time the wire can be introduced through the oblique side entrance just as easily as it can 75 through a side entrance parallel with the axis of the hole a .

I am aware that an insulator has been formed with a V-shaped groove in one side to receive the wire; also, that the upper end of an insulator has been formed with an open top slot having at its bottom lateral incisions for receiving the wire; and, also, that an insulator has been formed with an annular groove and projecting ears arranged above and below the 85 groove for receiving the wire. Such, therefore, I do not claim.

What I claim as new, and desire to secure by Letters Patent, is—

1. A telegraph-insulator constructed within 90 its body with a transverse hole, a , extending in a straight line from side to side thereof, and provided with rectilinear entrance b , approximately the length of the transverse hole, and having its lower edge, c , extended laterally in 95 an outward direction beyond the upper edge, c' , and terminating below said upper edge, c' , to leave the rectilinear side entrance unobstructed for the free lateral insertion of the line-wire, substantially as described. 100

2. A telegraph-insulator having constructed within its body a transverse hole, *a*, extending from side to side thereof, and provided with a rectilinear side entrance, *b*, arranged 5 in a line oblique to the longitudinal axis of the insulator, said side entrance extending approximately the length of the transverse hole and having its lower edge, *c*, projecting laterally in an outward direction beyond, but 10 terminating below, the upper edge, *c'*, to leave

the oblique side entrance unobstructed for the lateral insertion of the wire, substantially as described.

In testimony whereof I have hereunto set my hand and seal in the presence of two sub- 15 scribing witnesses.

JOHN O'BRIEN. [I. S.]
